SPARK PLUG ELECTRODE AND METHOD
OF MAKING SAME

Cornelius J. Dusseau, Toledo, Ohio

Application February 20, 1943, Serial No. 476,528

6 Claims. (Cl. 29—25.17)

1

This invention relates to spark plugs, and more particularly to electrodes of spark plugs and to the methods of making the same.

In the prior art, spark plug electrodes of the ring types having one or more prongs to cooperate with a center electrode to form the firing gap, have been made from stampings of sheet material but have been relatively inefficient for long continued use in heavy duty internal combustion engines, for example, airplane engines, because the thickness of the individual prongs at the firing gap was too thin to give the necessary gap life required to aviation type spark plugs. The thickness of the prongs was materially reduced as compared with the original thickness of the sheet material from which the electrode was stamped due to the attenuation of the material during the forming process to obtain the desired contour of the prongs. The relatively thin sections of the prongs reduce to a certain extent the capacity for heat conduction so that the temperatures during operation in internal combustion engines at the tips of the prongs tends to become relatively high which further accelerated erosion of the material by sparking. This acceleration in material erosion tended to shorten the useful life of the spark plug and made it necessary to overhaul the airplane engines after a shorter period of operation.

The present invention provides a multi-prong electrode for a spark plug which obviates these difficulties by giving the prongs of the electrode substantially the same thickness as the thickness of the original sheet from which the electrode is fabricated. This desirable result is brought about by a series of steps in the forming operation in which the outside diameter of the ring of the electrode is originally stamped to a dimension materially larger than the final outside dimension. The electrode itself is then compressed from the larger outside diameter to the smaller outside diameter of the final electrode in a constricting press so that the juxtaposition of the upwardly-turned prongs is changed to a closer relation whereby more material is available for the formation of the prongs arising from the large size of the original outside diameter of the electrode. This method of forming the electrode has the advantage of avoiding the attenuation of the material which previously resulted in a relatively thin section or thickness in the prongs of the completed electrode.

The fact that the original step in the formation of the electrode when the blank is first struck from the sheet material is made with a larger

2

outside diameter allows the use of dies and punches having greater strength and durability. During the manufacturing process the punches and dies used in the fabrication of electrodes are given a longer life expectancy so that the cost of fabricating these electrodes is materially reduced.

It is, therefore, a principal object of this invention to provide multi-prong electrodes for use in spark plugs in which the amount of material available for spark erosion at the spark gap is controllable within relatively wide limits.

It is a further object of this invention to provide a multi-prong electrode for use in spark plugs wherein the sparking surface of the electrode may be controlled so as to maintain the sparking surface suitable for a particular firing condition in the engine cylinders.

It is a further object of this invention to provide a method of making multi-prong spark plug electrodes wherein the stock used for forming the prongs is obtained from material within the perimeter of the electrode and thereafter collapsing the perimeter whereby the thickness of the prong adjacent the spark gap is approximately the same thickness as the sheet stock from which the electrode is fabricated.

It is a further object of this invention to provide a machine suitable for making multi-prong spark plug electrodes, which collapses the supporting web of the electrode from a relatively large diameter to the predetermined diameter of the completed electrode.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Fig. 1 is a perspective view of sheet stock, showing the various steps during the early forming operations of the electrode.

Fig. 2 is a plan view, partly in section, of a die used in one step of forming the electrode and is taken along the line 2—2 of Fig. 3.

Fig. 3 is a sectional elevation of the die, taken along the line 3—3 of Fig. 2.

Fig. 4 is a perspective view of the electrode, showing the shaving operation.

Fig. 5 is a sectional elevation, showing the relation of the prongs of the electrode.

Fig. 6 is an elevational view, partly in section, of the spark plug to which the electrode has been applied.

Fig. 7 is a sectional elevation of a modification of the electrode form.

Referring to the drawings, particularly to Fig. 6, a spark plug is shown having a shell 10 provided with a threaded portion 11 by which the spark plug is adapted to be screwed into the cylinder block of an engine. A ceramic insulator 12 is provided which encloses a central electrode 13, whose lower end 14 projects from the bottom of the insulator 12 and cooperates with electrode 15 which is conveniently brazed or otherwise attached to the lower end of the threaded portion 11 of the shell in a recess 16. The prongs 17 of the electrode 15 cooperate with the tip 14 of the central electrode to form the spark gap of the spark plug. The details of construction of the spark plug of this type are well known in the art and need not be described in further detail. This invention relates particularly to the ground electrode 15 and to the methods of making the same.

Referring now to Fig. 1, a strip of sheet material 18 is provided whose width is slightly larger than the external diameter of the blanked form 19 of the electrode, this width being necessary in order to facilitate the blanking operations in a punch press (not shown). The thickness of the strip sheet stock 18 is selected with a view of obtaining sufficient thickness to give necessary strength to the connecting web 20 of the electrode, which is of the ring type having preferably three inwardly projecting prongs 21 which are shown in an early step of the fabrication of the electrode in Fig. 1. The thickness of the sheet stock 18 is one of the factors which predetermines the thickness of the prongs and if a greater amount of material is desired in the prongs to provide more material available for gap erosion, a thicker sheet may be selected.

The first step in the forming operations of the electrode comprises piercing a triangular-shaped aperture 22 which provides faces 22a which at a later period become the end faces of the prongs 21. The next step in the forming operations is another piercing step wherein three bights 23 are struck from the material which communicate with the aperture 22 to form a cloverleaf-shaped aperture as shown in Fig. 1. The next step in the forming operations comprises bending of the prongs 24 which project inwardly in the second step of the operation to form the cloverleaf aperture to the condition shown in the left-hand position of Fig. 1 wherein the prongs 24 have been bent substantially to normal use position or angularly to the plane of the sheet material 18. Immediately after the bending of the prongs, and preferably a part of the same step, the electrode 19 is blanked from the sheet as is clearly shown. This leaves a circular aperture 25 in the sheet stock 18 as is clearly shown. The blanked electrode 19 is shown immediately below the aperture 25.

The diameter of the aperture 25, and the outside diameter of the blanked electrode 19, is such that the web 20 is given a ring formation to support the upwardly bent, inwardly disposed prongs 21 so that the length of prong desired, may be obtained from the amount of material available in the strip sheet 18 while the unbent prongs are still in the plane of the sheet stock as shown at 24. The prongs, as shown at 21, are substantially the same thickness as that of the sheet 18 and are

bent upwardly as shown without attenuating the material in the prongs to any great extent.

These four steps of piercing, forming and blanking are preferably performed by a multiple die having three stages, the first of which pierces the aperture 22 to form the end faces of prongs 24, the second step which is also a piercing operation forming the prongs 24 by striking the cloverleaf aperture; and the third stage performing the upward bending of the prongs 21 and the blanking operation of the web 20. These four steps are illustrated with reference to the piece of sheet material 18 in Fig. 1. With the sheet material 18 in the form of a long strip, a continuous operation may be performed by advancing the strip from right to left as shown in Fig. 1, leaving scrap material in the form of a strip 18 pierced by a series of apertures 25.

As has already been discussed, the outside diameter of the blanked electrode 19 is considerably larger than the outside diameter of the completed electrode 15 as mounted in the plug shown in Fig. 6. The blanked electrode 19, by reason of its larger outside diameter, disposes the upwardly-bent prongs 21 in a relation having considerable space between the prongs inasmuch as the inside surfaces of the prongs 21 fall in the surface of a cylinder considerably larger than the diameter of the tip 14 of the center electrode and would give too wide a gap if the blanked electrode were to be mounted in a plug. This invention provides a method whereby web 20 of the blanked electrode 19 may be collapsed uniformly along radial lines so that the outside diameter of the electrode is decreased to substantially the outside diameter of the completed electrode. The diameter of the collapsed electrode is still allowed to remain slightly larger than the finished electrode in order that a shaving operation, illustrated in Fig. 4, may be performed to provide the electrode with the exact outside diameter desired.

The dies necessary to perform the operations of piercing, forming and blanking are well known in the art and need not be described in further detail.

In order to perform the collapsing operation wherein the web 20 is collapsed to a smaller diameter, a novel form of die is provided as is generally shown in Fig. 2. In this figure a plan view 50 of the die is shown just after collapsing operation of the blanked electrode has been completed. The die is provided with three reciprocating bars 26 positioned in an angular relation 120° apart and are adapted to reciprocate in this angular relation 55 toward a common center. Each sliding bar 26 is provided with a square aperture 27 through which projects a square cam stem 28 in substantially normal relation thereto. These stems 28 are shown in transverse section in Fig. 2 and in longitudinal section in Fig. 3, only one being shown in the latter figure.

Referring to Fig. 3, a cam section 29 is provided on the stem 28 at substantially a mid point thereof so that when the stem 28 is retracted toward the left (as shown by the arrow) it will be clear that the action between the cam section 29 and the aperture 27 will cause a retreat of the bar 26 in an outwardly direction from the common center of action of the three slide bars. The slide bars 26 are provided with guides 30 cooperating with each side of the bar to maintain the linear movement converging toward the common center.

In order to move the stem 28 in and out of the apertures 27 of the slide bars 26, a head 31 is provided which preferably is attached to a punch

press such as is well known in the art and need not be described in detail. The punch press (not shown) reciprocates the head 31 in the well known manner so as to advance or withdraw the three cam stems 28 through the apertures 27 of the three slide bars 26. Each of the three stems 28 is provided with a cam section 29 at exactly the same longitudinal position so that the three slide bars 26 advance and retreat simultaneously to and from their common center of action as the operating head 31 changes its longitudinal position with reference to the slide bars. The slide bars 26 are held in a plane through the action of the guides 30 so that the longitudinal movement of the stem 28 with reference to the apertures 27 will give a uniform cam action.

The forward faces of the slide bars 26 are given a wedge-shape formation 26a and terminate in an arc portion 26b which has the same radius as the outside diameter of the electrode web after the constricting operation is completed. The arc 26b, on the forward face of the slide bar 26, extends for 120°, measured from the common center of action so that the three slide bars 26, by each covering 120° of arc, will form a complete circle circumscribing the perimeter of the constricted electrode. In order that the slide bars 26 may have ample strength to apply the necessary force to accomplish the constricting operation on the electrode, they are made relatively thick and the forward faces are chamfered at 26c so that the most advanced portion is adjacent the lower side of the slide bar 26 where the slide bar 26 cooperates with an anvil 35. The anvil 35 cooperates with one side of the web of the electrode while the slide bars 26 cooperate with the perimetrical edge thereof. A splined aperture 35a is provided in the anvil through which a movable member 36 is adapted to reciprocate longitudinally in a line parallel to the reciprocating action of the cam bars 28. The movable member 36 is of splined formation to prevent rotation in aperture 35a and is provided with a head 37 adjacent its lower end which cooperates with a transversely reciprocating bar 38 by a cam formation 39 conformed as a flanged groove gripping the head 37. As the bar 38 is reciprocated in the direction of the arrow shown in Fig. 3, through manual manipulation of a lever 40, the movable member 36 is thrust to the right or downwardly in the aperture 35a of the anvil 35, performing a stripping action on the electrode. The anvil 35 is conveniently embedded in a base 41 as shown with the aperture 35a extending through both. The base 41 is provided with a slot 42 in which the reciprocating bar 38 moves. The lever 40 moves the reciprocating bar 38 by means of a pin and slot arrangement 43, the lever being adapted to move about a pivot 44 as shown in phantom in Fig. 2.

The upper end (left-hand end Fig. 3) of the movable member 36 is contoured in a manner to give the electrode its final form, having reference to the shape of the prongs 47 and the conformation of the clover-leaf opening 23 in the electrode. For this purpose a central spindle 45 is provided on the movable member 36, flanked by bosses 46 which fit into cloverleaf-shaped openings 23 of the electrode. The central spindle 45 of the movable member 36 cooperates with an aperture 47 of a movable die member 48 which is conveniently attached to the head 31 of the punch press and adapted to be reciprocated thereby at the same time that the cam bars 28 are being reciprocated. The aperture 47 is preferably positioned in the end of a knockout pin 49 which moves concur-

trically with the die portion 48. The forward, or lower, face 50 of the die portion 48 is formed as a truncated cone so as to fit between the chamfered forward faces 26c of the slide bars 26 with the face 50a cooperating with the face of the electrode whose opposite face rests on the anvil 35 and the movable member 36, the electrode being formed by relative longitudinal movement between the die portion 48 and the anvil 35. The electrode is also being formed substantially simultaneously by the lateral movement of the three slide bars 26 moving in toward a common center under the action of the cam bars 28.

A cycle of operation of this machine preferably follows the sequence given hereinafter: In the opening phase the head 31 of the punch press is retracted to the left, in the direction of the arrow shown in Fig. 3, to a point where the portion of the cam bars 28 beyond the cam section 29 cooperate with the apertures 27 in the slide bars 26. Inasmuch as the cam sections 29 are displaced outwardly, the slide bars 26, under control of the portions of the cam bars 28 positioned beyond the cam sections 29, will be disposed in a position most remote from the common center of action. This position of the slide bars 26 is shown in phantom in Fig. 2 which shows the slide bars in their most outward position. The arc surfaces 26b are sufficiently separated so that the blanked electrode 19, as shown in Fig. 1, which is to be collapsed inwardly to a smaller outside diameter, is readily placed between the arc surface and upon the anvil 35 and the forward face of the reciprocating member 36. Inasmuch as the diameter of the central spindle 45 is somewhat smaller with reference to the juxtaposition of the prongs 21 of the blanked electrode 19, and the bosses 46 are somewhat smaller than the cloverleaf openings of the blanked electrode, no difficulty will be experienced by an operator in positioning the blanked electrode upon the end of the movable member 36 to its resting place on the anvil. The manual lever 40 controlling the position of the movable member 36 is substantially in the position shown in solid lines in Fig. 2 with the reciprocating bar 38 in substantially the position shown in Fig. 3, that is with the head 37 positioned at a point near the highest portion of the cam surface 39.

With the parts in this position, the constricting operation on the electrode may begin. The operator places the blanked electrode 19, as shown in Fig. 1, into position on the end of the movable member 36 so that the central spindle 45 is placed between the prongs 21 with the bosses 46 cooperating with the cloverleaf openings between the prongs and the web 20. The punch press is then started in operation which advances the head 31 to the right, as shown in Fig. 3, so as to bring the cam section 29 into operable relation with the aperture 27 in the slide bars 26 which simultaneously advances all three slide bars inwardly to the point where they contact the perimeter of the web 20 of the blanked electrode. The die 48, being also attached to the head 31 of the punch press, advances toward the center spindle 45 of the movable member 36. When the cam section 29 has passed substantially through the aperture 27 of the slide bars 26 which are moved inwardly thereby, the outside diameter of the web 20 of the blanked electrode 19 is collapsed inwardly and decreased to the diameter of a circle formed by the arcs 26b, positioned on the forward faces of the three slide bars 26.

Thereafter the die member 48 moves into a cavity formed between the slide bars 26 to thrust

the electrode against the anvil 35 within the curved faces 26b of the three slide bars 26. This action irons the face of the electrode and, through the action of the knockout pin 49, the ends of the prongs are ironed at the same time. The stroke of the head 31 is adjusted so that the space between the movable bars 26 is such that the blanked electrode positioned therein is conformed to the desired dimensions with small openings being provided between the slide bars 26 to allow excess material to flow outwardly. This is clearly shown in Fig. 4 where small nibs 60, formed on the perimeter of the web 20a, are shown, this being excess material.

Upon completion of the forward stroke of the head 31, the direction of movement thereof is reversed to the left as shown in Fig. 3, which causes a retreat outwardly of the slide bars 26 and of the die member 48. At this point force is applied to a rod 61, movable in an aperture 62 in the head 31, to advance the knockout pin 49 with reference to the die 48. The action of the knockout pin 49 releases the electrode from the forward end of the die member 48 so as the head 31 retreats the electrode will remain in position upon the forward end of the movable member 36. The movable member 36 is then retracted downwardly by manual reciprocation of the bar 38 to strip the constricted electrode from the forward face of the movable member 36 so that an operator may reach into the cavity of the die to remove the constricted electrode member. The operator then places another blanked electrode member 19 in position in the die cavity and a new cycle of operation begins.

The outer dimension of the constricted electrode member is made slightly larger than the desired outside diameter of the completed electrode. A shaving operation is then performed with dies that are well known in the art to remove the surplus material, as is shown in Fig. 4. The electrode 20a has the desired outside diameter and a ring 20b has been shaved from its perimeter as is well understood in the art and need not be described in greater detail.

The completed electrode is then positioned in the shell 10 of the spark plug, as shown in Fig. 6, by brazing, or welding, or the like.

In Fig. 7 a modification of the completed electrode is shown in which the thickness of the material at the base of a prong 65 has been substantially reduced in thickness by bumping at 66 so that the stiffness of the prong is substantially reduced to facilitate bending of the prong 65 with relation to the tip 14 of a center wire (Fig. 6). The form of the electrode shown in Fig. 5 provides the prongs of the electrode with the same diameter throughout its length with the base of the prong being displaced a slight angle, for example 7°, with reference to the plane of the connecting web. In many cases this type (Fig. 5) electrode has the disadvantage that adjustment of the prongs by bending so as to vary the spark gap between the prong and the tip of the center wire is made very difficult due to the inherent stiffness of the prong. Furthermore, the fact that the angular displacement between the prong and the plane of the supporting web is small, there is little tolerance to allow for any substantial gap adjustment by bending.

In Fig. 7 the angle between the prong and the plane of the supporting web has been increased to 30° which gives a substantial tolerance to allow displacement of the prong inwardly by bending to allow for spark-gap adjustment. The base 65

of the prong is also reduced in thickness by bumping which decreases the stiffness of the prong and allows more ready adjustment of the prong during change of spark gap length. The bumping operation, which decreases the cross section at 66 of the completed electrode as shown in Fig. 7, is preferably carried out by changing the conformation of the forward face of the movable member 36 so that the prong is conformed through the inter-action of the die member 48, the anvil 35 and the movable member 36. In other respects the same steps are followed forming this type of electrode as have already been described with reference to electrode shown in Fig. 5.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope 30 of the following claims beyond the requirements of the prior art.

What is claimed:

1. The method of forming a multi-prong ground electrode of the ring type suitable for use with spark plugs, comprising, piercing, blanking and forming the electrode from sheet material in a series of steps, maintaining the diameter of the ring supporting the inwardly disposed prongs substantially larger than the dimension of the ring in the completed electrode, collapsing the ring in a radial direction to reduce the diameter of the ring to substantially the diameter of the completed electrode, and thereafter attenuating a portion of the prongs adjacent the ring to reduce the section thereof.

2. The method of forming multi-prong ground electrodes of the ring type suitable for use with spark plugs, comprising, piercing an aperture in sheet stock, the sides of the aperture forming end faces of the several prongs, piercing a series of bights in communication with the aperture to form inwardly projecting prongs, forming the inwardly projecting prongs to an angle substantially normal to the plane of the sheet stock, blanking a ring from the sheet stock supporting the inwardly projecting prongs, said ring having a diameter substantially larger than the diameter of the completed electrode, collapsing the ring in a radial direction to change the juxtaposed relation of the inwardly projecting prongs to decrease the diameter of the ring to substantially the diameter of the completed electrode and thereafter attenuating a portion of the prongs adjacent the supporting ring to reduce the section thereof.

3. The method of forming multi-prong ground electrodes of the ring type suitable for use with spark plugs, comprising, piercing an aperture in sheet stock, the sides of the aperture forming end faces of the several prongs, piercing a series of bights in communication with the aperture to form inwardly projecting prongs, forming the inwardly projecting prongs to an angle substantially normal to the plane of the sheet stock, blanking a ring from the sheet stock supporting

the inwardly projecting prongs, said ring having a diameter substantially larger than the diameter of the completed electrode, collapsing the ring in a radial direction to change the juxtaposed relation of the inwardly projecting prongs to decrease the diameter of the ring to substantially the diameter of the completed electrode, attenuating a portion of the prongs adjacent the supporting ring to reduce the section thereof, and thereafter shaving the outer edge of the electrode to the exact dimension of the final electrode.

4. The method of forming multi-prong metallic ground electrodes for spark plugs comprising piercing, blanking, and forming the electrode from sheet stock with a ring forming a connecting web between the inwardly and downwardly projecting prongs, a portion of said downwardly projecting portions of said prongs forming sparking surfaces, said ring having a diameter substantially larger than the diameter of the completed electrode, placing the sparking surfaces of the prongs in predetermined relative relation with each other by collapsing the web inwardly, and substantially simultaneously ironing the metal of the prong at and adjacent the sparking surfaces.

5. The method of forming a multi-prong metallic ground electrode for spark plugs comprising piercing, blanking, and forming the electrode in a series of steps to form a ring-like web having inwardly and downwardly projecting prongs having sparking surfaces on the downwardly projecting portions thereof, said web having a diameter substantially larger than the diameter of the web of the completed electrode, placing the sparking surfaces of the prongs in predetermined relative relation with each other by collapsing the web inwardly and substantially simultaneously

ironing the metal of the prongs at least at the sparking surfaces.

6. The method of forming multi-prong metallic ground electrodes of the ring type suitable for use with spark plugs comprising, piercing an aperture in sheet stock, piercing a series of blights in communication with the aperture to form inwardly projecting prongs, forming a portion of the inwardly projecting prongs to an angle substantially normal to the plane of the sheet stock to comprise sparking surfaces, blanking a ring from the sheet stock supporting the inwardly and downwardly projecting prongs, said ring having a diameter substantially larger than the diameter of the completed electrode, placing the sparking surfaces of the prongs in predetermined relative relation with each other by collapsing the web inwardly, substantially simultaneously ironing the metal of the prongs at least at the sparking surfaces, and thereafter further decreasing the diameter of the ring by shaving while maintaining the predetermined relations of the sparking surfaces.
